(57) **CLAIM**

The ornamental design for a wheel, as shown and described.

DESCRIPTION

FIG. 1 shows a perspective view of a wheel according to the present invention.

FIG. 2 shows a front view of the wheel of FIG. 1.

FIG. 3 shows another perspective view of the wheel of FIG. 1.

FIG. 4 shows a rear view of the wheel of FIG. 1; and,

FIG. 5 shows a top view of the wheel of FIG. 1, the bottom, left and right side views being substantially identical to the top view.

Portions or features of the wheel not shown in the drawings form no part of the claimed design. Portions or features of the wheel shown in broken lines form no part of the claimed design.

1 Claim, 5 Drawing Sheets
